(57) **CLAIM**

We claim the ornamental design for a washing appliance agitator having spiral baffle, as shown.

DESCRIPTION

FIG. 1 is a top perspective view of the washing appliance agitator having spiral baffle.

FIG. 2 is a bottom perspective view thereof.

FIG. 3 is a top plan view thereof.

FIG. 4 is a side elevational view thereof, all other side elevational views being the same; and,

FIG. 5 is a bottom plan view thereof.
